United States Patent Office.

R. F. LIVERMORE, OF STARKSBORO, VERMONT.

Letters Patent No. 74,101, dated February 4, 1868.

IMPROVEMENT IN SAP-SPOUT.

The Schedule referred to in these Letters Patent and making part of the same.

TO ALL WHOM IT MAY CONCERN:

Be it known that I, R. F. LIVERMORE, of Starksboro, in the county of Addison, and State of Vermont, have invented a new and improved Sap-Spout; and I do hereby declare that the following is a full, clear, and exact description thereof, which will enable others skilled in the art to make and use the same, reference being had to the accompanying drawings, forming part of this specification.

Figure 1 is a section, through the line $a a$, fig. 2, showing the spout when in the tree.

Figure 2 is a top view of the spout.

Similar letters of reference indicate corresponding parts.

This invention consists of a metallic sap-spout, of such a form that many important advantages are secured over the common wooden spout, as heretofore used, which advantages will be hereinafter fully explained.

This sap-spout is made of metal, and consists of a spout, A, of any proper length, attached and forming a part of the head D. This head is perforated with a hole, h , for the sap to pass through into the spout A, and thence into the bucket or tub. This head is slightly bevelled on its exterior, as shown at a , and is formed with a concave surface on that part that faces the hole or tap in the tree, and the said bevelled exterior and the concavity form a sharp edge, a' , which has an important function, and will be hereinafter explained. From the central part of the said concavity projects the screw S, for holding the spout firmly to the tree B, whereby the head D covers the chamber C, which is made in the tree, and the edge a' , pressing firmly against the bark, prevents leakage. The chamber C is made by the ordinary tapping-bit, and all that is necessary to attach my metallic spout is to place the screw in the centre of the hole or chamber made in the tree, and turn it till the edges a' press firmly against the bark around the hole or chamber, and the bucket or pail hung thereon, the spout being provided with a projection, E, to retain the bucket in its place. The sap flows from the walls of the chamber C, and, flowing through the hole h , is carried by the spout A, and thence falls into the bucket. The spout can be constructed of any desired metal, though cast iron is perhaps the cheapest, and, if made of this metal, can be furnished very cheaply. This form of a sap-spout admits of the use of different-sized tapping-bits, but is designed particularly to allow the use of a small hole in the tree, thereby to lessen the injury to the same, as, from repeated experiments, it has been clearly proven that there is no appreciable difference in the quantity of sap discharged from a large or small hole. This spout surrounds the exterior of the chamber C, instead of partially plugging the interior of the same, which latter materially lessens the flow of sap, and is the only method practicable with the wooden spouts as now used. The head D, by means of the edge a' , perfectly covers the hole in the tree, protecting it from the drying effect of the wind or sun, while the chamber C is left free and clear, allowing the sap to flow from all parts of it, and by hanging the tub or bucket upon the spout, the expense and injury to the tree, of spike and nails, are avoided.

I claim as new, and desire to secure by Letters Patent—

As a new article of manufacture, a cast-metal sap-spout, constructed as described, consisting of the spout A, having the head D perforated at h , and provided upon its end with the concave surface, in the centre of which the screw S is secured, the exterior surface of said head bevelled at a to form the edge a' , and having upon its upper side the projection E, as herein shown and described.

R. F. LIVERMORE.
